UNITED STATES PATENT OFFICE.

BYRON D. JACKSON, OF ERIE, PENNSYLVANIA, ASSIGNOR TO MODERN TOOL COMPANY,
OF ERIE, PENNSYLVANIA, A CORPORATION OF PENNSYLVANIA.

DRIVING DEVICE.

1,072,616.

Specification of Letters Patent.

Patented Sept. 9, 1913.

Application filed November 7, 1912. Serial No. 730,097.

To all whom it may concern:

Be it known that I, BYRON D. JACKSON, a citizen of the United States, residing at Erie, in the county of Erie and State of Pennsylvania, have invented new and useful Improvements in Driving Devices Having Intermittent Movement, of which the following is a specification.

This invention relates to driving devices having intermittent movement and consists in certain improvements in the construction thereof as will be hereinafter fully described and pointed out in the claims.

There are many machines in which there is a driving and a driven element, one mounted on the other, and one arranged to slide on the other, in which the parts are given rotative movement and the driving pressure between the parts or elements is intermittent as for instance in a reversing mechanism where the clutch element has at each reversal a different direction of driving pressure. Such mechanisms have ordinarily been provided with a square spline and groove but it is difficult to retain these in proper working order due to the constant strain upon some parts of metal.

The object of the invention is to improve this driving device.

In the accompanying drawings, I have shown the invention as applied to a reversing device.

Figure 1 shows a perspective view of the clutch block of the reversing device. Fig. 2 is a plan view of such device. Fig. 3 is a front view of a part of the carriage showing the reversing stop and rock lever. Fig. 4 is an end view, partly in section of a part of the connecting mechanism for actuating the reversing device.

1 marks the reversing shaft, 2 the clutch block, 3 a cylindrical key, 4 a semi-cylindrical keyway and 5 a semi-cylindrical keyway completing with the keyway 4 a cylindrical keyway to receive the cylindrical key 3. The clutch block in this instance is mounted on a slight enlargement 1^a of the shaft and in its use is moved longitudinally along the shaft back and forth to effect a reverse of the driving mechanism. At each reversal the direction of strain on the key is reversed. I have found that where a key especially of a cylindrical shape is used in such a keyway with devices having inter-

mittent or reversing motion the action on the key revolves it so that new surfaces are constantly presented. I have shown in Fig. 2 a reversing mechanism to which such a keyway is applied. I wish to be understood that the specific type of reversing mechanism forms no part of this invention.

The mechanism shown is arranged for the carriage mechanism of a grinding machine. This is driven by a drive wheel 6. The drive wheel 6 is mounted on a shaft 7 journaled in the bearing 8. The bearing 8 extends from the bracket 9 which is secured to the frame 10 of the machine. A gear 11 is fixed on the shaft 7 and meshes a gear 12. The gear 12 is carried by a shaft (not shown) carried by a bearing 13. The gear 12 is secured to a beveled gear 14. The beveled gear meshes the gears 15 and 16, said gears being mounted on the shaft 1. Each of these gears has a clutch surface (not shown) for engaging the detent ends of the clutch block 2. The clutch block has the circumferential groove 17 into which the pins 18 extend. The pins are carried by the forked lever 19. The forked lever is pivoted on a pin 20 carried by the bracket 9. The lever 19 has an extension 21 which extends between the arms 22 of an actuating lever 23. The actuating lever 23 is connected by a link 24 with a rock lever 25. The rock lever is fixed on the rock shaft 26. A lever 27 is fixed on the rock shaft 26 in the path of the stops 28 on a carriage 29. It will be readily observed that as the carriage stops come into contact with the lever 27, the movement of this lever is communicated to the clutch block 2 so as to throw the clutch block 2 from the gear 15 to gear 16 or vice versa, thus reversing the direction of movement of the shaft 1, the gears 15 and 16 being driven in opposite directions by reason of the fact that they mesh with opposite sides of the gear 14.

A clutch member 30 is fixed on the shaft 1 and engages a clutch member 31 also on said shaft. A beveled gear 32 is secured to the clutch member 31 and meshes with a gear 33 designed to drive the carriage. Any desired connecting mechanism may be arranged between the gear 33 and the carriage.

It will be noted as the shaft 1 is reversed through the action of the gears 15 and 16

the key 3 is subjected to pressures varying in direction and it is also relieved of pressure intermittently. This being so, the key revolves presenting slightly different surfaces to the driving strain with each action of the machine. In this way, the key can be kept in perfect condition so that the reversing movement of the block 2 remains perfectly free. It will be understood, of course, that more than one key 3 may be used if desired.

What I claim as new is:—

1. The combination of a driving element and a driven element, one slidably mounted upon the other and having keyways forming a cylindrical opening; a cylindrical key in said opening; and means for im-

parting intermittent movement to the driving element.

2. The combination of a driving element 20 and a driven element, one slidably mounted upon the other and having keyways forming a cylindrical opening; a cylindrical key in said opening; and means for imparting an intermittent and reversing 25 movement to the driving element.

In testimony whereof I have hereunto set my hand in the presence of two subscribing witnesses.

BYRON D. JACKSON.
